METHOD OF EFFECTING COMBUSTION OF PARAFFINIC HYDROCARBON GASES AND VAPORS

Theodore Nagel, Brooklyn, N. Y.

Application October 24, 1946, Serial No. 705,270

1 Claim. (Cl. 158—117.5)

1

1

1

My invention is directed to a method of effecting combustion of paraffinic hydrocarbon gases and vapors, and its primary object is the production of effective heat with substantially less fuel than required when burned by conventional methods.

Gaseous hydrocarbons of the paraffinic series (C_nH_{2n+2}) to which my invention relates, namely, methane, ethane, propane, and the lighter weight paraffinic vapors—constituents of natural gas—having a high hydrogen content, produce comparatively low-radiant flames of relatively low luminosity when burned by conventional methods, the combustion of hydrogen producing a non-luminous, blue flame.

Furthermore, in the combustion of these fuels by conventional methods only a very small portion of the carbon content of the hydrocarbons is liberated in the form of glowing solids—the source of radiant energy. It is obvious, therefore, that, because of the high hydrogen content of the fuels and the deficiency of glowing carbon particles, which, in addition, are dispersed and scattered throughout the widely dispersed flame, radiance is limited to a low degree of intensity, yielding effective heat far below the maximum inherent in the fuel.

My invention provides an improved method of effecting combustion of paraffinic hydrocarbon gases and vapors, wherein, before mixing the fuel with air for complete combustion, I decompose hydrocarbons to liberate carbon particles by mixing the fuel with air sufficient to support ignition, igniting the mixture, and flowing the ignited mixture in the form of a thin-wall, annular, diverging stream until carbon particles are liberated as ignited solids throughout this ignited gaseous fuel stream.

The diverging stream of ignited fuel, with carbon particles disseminated throughout the same, is then caused to flow into an annular, converging stream of combustion air, sufficient in volume to support combustion of the fuel.

By this method it will be apparent that a highly concentrated flame of intense, radiant luminosity is produced in that not only carbon is liberated as ignited solids disseminated throughout the ignited gaseous fuel stream prior to contacting this stream with combustion air, but the stream of combustion air converges toward the axis of flow, so that the burning fuel-and-air mixture is concentrated around the axis of flow instead of being dispersed to fill the furnace chamber with burning fuel, as in conventional methods, and extremely rapid combustion is,

therefore, effected in a relatively restricted area. Furthermore, glowing carbon particles permeate the extremely rapidly burning fuel, so that not only is a highly concentrated flame produced, but a flame of intense radiant luminosity, as distinguished from the diffused and characteristic relatively non-luminous flame produced when burning natural gas by conventional methods.

In the accompanying drawing Fig. 1 is a top plan view of the diverging member or hood employed in the practice of my method, and

Fig. 2 is a section on the line 2-2 of Fig. 1.

Fig. 2 is a view of the furnace.

Referring to the drawing in detail, 2 designates a furnace front provided, preferably, with convergent fuel opening or throat 4 through which fuel is admitted to the combustion chamber of the furnace. Suitably supported in front of this opening is an annular, diverging member 6 forming a chamber, spaced a short distance from the throat, thereby providing an opening 8 between the outlet edge of member 6 and the edge of throat 4, through which opening the combustion air flows in an annular, converging stream into the furnace throat or opening.

25 In the wall of member 6 are air inlets 10, through which air flows in volume sufficient to support ignition of the fuel.

12 designates the fuel supply line which is inserted into the apex of diverging member 6. Inserted in the outlet of this fuel supply line or pipe 12 is a diverging member 14, which is surrounded by the diverging wall outlet end 16 of the fuel supply pipe from which the member 14 is spaced so as to provide a diverging annular channel 17, through which the gas flows and emerges in a thin-wall, annular, diverging stream.

In operation, natural gas is caused to flow continuously through supply line 12 and between the members 14 and 16. By reason of the fact that the members 14 and 16 form a narrow, annular, diverging channel 17, the gas will flow therefrom paralleling the wall of the member 6 in a thin-wall, annular, diverging stream, mixing with air admitted through the air inlets 10 in the wall of member 6 sufficient for supporting ignition. The mixture is ignited inside the chamber member 6 by means of a torch or by other suitable means common to this art such as igniter electrodes 7. The gas feed pressure and the dimensions of member 6 are such that, by the time the ignited gaseous fuel flowing in a thin-wall, annular, diverging stream through the chamber formed by the member 6 has reached the outlet of this chamber, hydrocarbons have been decomposed, liberating ignited carbon par-

ticles throughout the ignited gaseous mixture. The ignited fuel then flows into the annular, converging stream of combustion air which flows through opening 8 and with which it intermixes and flows through throat 4 into the furnace.

Inasmuch as the ignited stream of hydrocarbon gas, in the form of a thin-wall, annular, diverging stream, is caused to flow and become dispersed into an annular, converging stream of combustion air, and inasmuch as the combustion air flows through opening 8 converging toward the axis of flow, it will be apparent that the ignited fuel-and-air mixture flows forward in a stream concentrated around the axis of flow, so that, instead of spreading out to fill the furnace chamber with burning fuel as in conventional methods of combustion, extremely rapid combustion is effected in a relatively restricted space, thereby producing a higher-temperature heat liberating zone than can be produced by conventional industrial methods of burning gas for the same fuel input.

Because of these facts and because of the fact that, prior to mixing with the combustion air, ignited carbon particles permeate the ignited gaseous fuel, the highly concentrated incandescent carbon particles within the highly concentrated heat liberating zone produce a flame of intense radiant luminosity, as distinguished from the characteristic, relatively non-luminous, widely dispersed flame produced when burning natural gas by conventional industrial methods.

What I claim is:

The method of effecting combustion of natural gas, which method comprises delivering the gas under pressure into a chamber having a diver-

ing wall in a thin-wall, annular, diverging, continuously flowing stream, mixing with the gas stream in said chamber air, sufficient for supporting ignition of the gas; igniting the mixture; advancing the ignited mixture along the divergent chamber wall in a thin-wall, annular, diverging stream until decomposition liberates ignited carbon particles; and directing into the thin-wall, annular, diverging stream of ignited gaseous fuel, permeated with ignited carbon particles as it leaves the divergent chamber wall, an annular stream of additional air converging across the discharge end of the divergent chamber wall and sufficient in volume to support complete combustion of the ignited gaseous fuel, thereby to produce an intensely radiant, luminous, concentrated flame.
